United States Patent

Des. 234,617
Patented Mar. 25, 1975

234,617

WHEELED TOY

Henry Lamb, 51 Bradford Drive,
Feeding Hills, Mass. 01030

Filed Apr. 6, 1973, Ser. No. 348,724

Term of patent 14 years

Int. Cl. D21—01

U.S. Cl. D34—15 D

FIG. 1 is a front left perspective view of the wheeled toy showing my new design;

FIG. 2 is a rear elevational view thereof; and

FIG. 3 is a rear right perspective view thereof.

I claim:

The ornamental design for a wheeled toy, as shown and described.
